(57) **CLAIM**

We claim the ornamental design for a handheld water flosser, substantially as shown and described.

DESCRIPTION

FIG. 1 is a front, right isometric view of a handheld water flosser.

FIG. 2 is a front elevation view of the handheld water flosser of FIG. 1.

FIG. 3 is a rear elevation view of the handheld water flosser of FIG. 1.

FIG. 4 is a right side elevation view of the handheld water flosser of FIG. 1.

FIG. 5 is a left side elevation view of the handheld water flosser of FIG. 1.

FIG. 6 is a top plan view of the handheld water flosser of FIG. 1; and,

FIG. 7 is a bottom plan view of the handheld water flosser of FIG. 1.

The broken lines shown in FIGS. 3 and 7 represent portions of the handheld water flosser that form no part of the claimed design.
